UNITED STATES PATENT OFFICE.

WILLIAM W. S. ORBETON, OF HAVERHILL, ASSIGNOR TO HIMSELF, GEO. W. CAMPBELL, OF BRADFORD, AND GEO. P. RUSSELL, OF HAVERHILL, MASS.

IMPROVED CLOTHES-DRIER.

Specification forming part of Letters Patent No. 55,208, dated May 29, 1866.

To all whom it may concern:

Be it known that I, WILLIAM W. S. ORBETON, of Haverhill, in the county of Essex and State of Massachusetts, have invented an Improved Clothes-Drier; and I do hereby declare the same to be fully described in the following specification and represented in the accompanying drawings, of which—

Figure 1 is a side elevation of my improved clothes-drying apparatus, the endless line being represented as passing through a door or window. Fig. 2 is a rear-end elevation of the said clothes-drying apparatus.

The nature of my invention consists in a peculiar construction and arrangement of certain parts of the said apparatus or drier, whereby nearly the whole length of the clothes-line is rendered effective for supporting washed garments while exposed to the sun or air for the purpose of being dried.

It also consists in a peculiar adjusting device, so applied that the axis of the wheel or its plane of revolution may be adjusted and fixed at any desirable angle.

The invention in question relates to that particular class of driers in which an endless line is caused to travel around two or more pulleys or wheels.

The object of my invention is to obtain the use of as much of the clothes-line as possible.

In the said drawings, H denotes a post or standard whose foot is to be placed in the ground or otherwise properly secured in any desirable position. The said post near its top part has a cylindrical or other proper shaped hole made transversely through it, the same being to receive one end, a, of the adjuster D, which has the form as shown in dotted lines in Fig. 2. The said adjuster is affixed to the post H, and clamped in any desired position, by means of a clamp-nut b, applied to the said end a, which has a male screw cut upon it to receive the said nut, b. From the upper end of the said adjuster a journal, d, extends upward and receives the hub I of the wheel A, whose under surface is supported by and revolves on the upper surface of the collar O.

By unscrewing the clamp-nut and turning the adjuster D the plane of revolution of the wheel may be either elevated or depressed, as circumstances may require. K is a screw-nut

which serves to confine the wheel A to its journal.

By giving the peculiar form to the adjuster D as shown in Fig. 2, I am enabled to readily adapt the wheel A to any desirable plane of revolution. In practice, such plane should be as nearly a horizontal one as may be, and maintain the endless line in its due place upon the wheel. The said wheel has a series of spokes or radial arms, L, extending from its hub, each of which at its outer end is terminated by a curved or crescent-shaped bar, M, formed as shown in the drawings. The object of this peculiar construction of the wheel is twofold: first, to prevent the line when filled with clothes from so sagging as to run off the wheel; and second, to prevent soiling or injuring the clothes while being revolved around the wheel and during the act of drying. Around the said wheel A an endless line, O, extends, and is carried around a sheave or pulley, S, attached to a post, P, such post being disposed at any suitable distance from the post H, and either within or without a building or shelter, as may be desirable.

In the drawings I have exhibited the line as extending through a space or window, which may be supposed to be arranged in the side of a building. In order to cause the said line to maintain a proper degree of tension around the said pulley and wheel, I connect the said pulley S to a short lever, h, the upper end of which is hinged to the said post P, as seen in Fig. 1. This lever is provided with a rope or chain, r, which, when the endless line has received the desired amount of tension, is to be firmly fastened to a pin or device extending from the post P, as seen in said Fig. 1.

From the above it will be seen that my improved drying apparatus possesses several important advantages: First, it can be compactly constructed, and besides, nearly the whole length of the line is rendered available. My said apparatus may be disposed entirely in the open air, or in a building, or a part may be in the open air and a part within a building or under a shed, as may be desirable. Instead of using a single wheel and a pulley, two wheels may be employed. Where long extent of line is required—say two hundred feet—a third wheel might be employed. In this latter case another

post would become necessary, which should be placed midway between the other two, and the wheel should be so arranged upon it as to support the lower portion of the endless line.

I am aware that the combination of an endless line with a shed and a straining device is not new. Therefore I do not claim such.

I claim—

1. The combination of the wheel A, the adjuster D, the pulley S, the posts H and P, or their equivalents, and the endless line o, with the lever h and its rope r, the whole being ar-

ranged so as to operate as and for the purpose set forth.

2. The adjuster D, constructed substantially in manner as set forth, and provided with a clamping-screw and nut, and a journal, d, respectively applied to the post H and the wheel A, the whole being arranged in manner and so as to operate substantially as set forth.

W. W. S. ORBETON.
